US00D925911S

(12) **United States Design Patent** (10) **Patent No.:** **US D925,911 S**
Sun (45) **Date of Patent:** **** Jul. 27, 2021**

(54) **SUITCASE**

(71) Applicant: **HEBEI ZHONGXING RUNCHENG LUGGAGE GROUP CO., LTD,**
 Shijiazhuang (CN)

(72) Inventor: **Jiacheng Sun**, Shijiazhuang (CN)

(73) Assignee: **HEBEI ZHONGXING RUNCHENG LUGGAGE GROUP CO., LTD,**
 Shijiazhuang (CN)

(**) Term: **15 Years**

(21) Appl. No.: **29/719,013**

(22) Filed: **Dec. 31, 2019**

(51) LOC (13) Cl. **03-01**

(52) U.S. Cl.

USPC **D3/279**

CLAIM

The ornamental design for a suitcase, as shown and described.

DESCRIPTION

FIG. 1 is a front, right and top perspective view of a suitcase showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the suitcase in which the design is embodied that forms no part of the claimed design.

1 Claim, 7 Drawing Sheets
